UNITED STATES PATENT OFFICE.

JOHN K. NORSTROM AND GEORGE C. BREIDERT, OF CHICAGO, ILLINOIS.

HEATING AND VENTILATING APPARATUS.

1,232,598.

Specification of Letters Patent.

Patented July 10, 1917.

Application filed November 5, 1913. Serial No. 799,276.

To all whom it may concern:

Be it known that we, JOHN K. NORSTROM and GEORGE C. BREIDERT, citizens of the United States, all residing at Chicago, in the county of Cook and State of Illinois, have invented certain new and useful Improvements in Heating and Ventilating Apparatus, of which the following is a specification.

10 This invention relates to improvements in heating and ventilating apparatus, and particularly to an automatically controlled system for electric-heating and forced draft ventilating.

15 In some of its features our invention is especially well adapted for use in street-railway cars, and we have shown herein an embodiment particularly designed to such use, but it will be understood that we do not limit our invention in its broader aspects to such installations.

20 In the system now most generally in use for heating street-cars, a series of heating coils are placed under the seats of the car and the current turned on or cut off by the motor-man or conductor whenever he thinks a change in the temperature of the car should be made. It is a well known fact that this system is most unsatisfactory as 25 it depends for its efficiency upon the care and attention given to it by the operators. In our improved system we have provided for automatic heat control, the controller, automatically governed in its movements by 30 a thermostat, operating to start or stop, (if desired) a ventilating fan and acting to vary the heat-supply, as by cutting in or out a plurality of electric heating coils positioned within the delivery duct of the fan.

35 A particular feature of our invention is the heater-element controller constructed to provide a shiftable member movable in opposite directions respectively, in response to a thermostat's response to rise and fall of 40 temperature; to provide a positive lock for said shiftable member in each position, and to govern the controlling circuit for its electro-responsive devices so that said circuit is active only when the thermostat responds to temperature changes.

45 A further feature of our invention resides in the provision of an adequate thermo-responsive apparatus for and connections for governing the controller. Another feature 50 of our invention, especially relating to car-heating is the mounting of the thermostat

outside of the compartment to be heated and ventilated, whereby it is more responsive to temperature changes, thereby varying the heating capacity of the apparatus 60 and preparing the interior of the compartment, prior to its being actually affected by the outside change. A further feature of our invention relates to the electrical heating installation, for provision of adequate, 65 readily-variable heater, in association with an air duct to give minimum obstruction to air flow.

70 Whereas we have shown and described the apparatus as applied to a street railway car, it is obvious that it would be equally efficient when used for heating and ventilating dwelling houses, public buildings or in fact any compartment or inclosure.

75 In the drawings, wherein we have illustrated a particular embodiment of our invention,

80 Figure 1 is a side elevation of a street railway car with parts broken away to show the installation of our apparatus.

85 Fig. 2 is a vertical longitudinal sectional view through the intake and discharge duct of our ventilating fan showing our improved heating coils in position.

Fig. 3 is a perspective view of a heating unit.

Fig. 4 is a wiring diagram showing the electrical connections between the various parts of the apparatus.

Fig. 5 is a plan view of our improved controller.

Fig. 6 is a side elevation of the controller.

Fig. 7 is a vertical transverse sectional view on line 7-7 of Fig. 6.

Fig. 8 is a fragmentary perspective view 95 showing the ratchet mechanism for moving and unlocking the slidable carriage of the controller.

Fig. 9 is a plan view of the relay.

Fig. 10 is a plan view with parts broken away of our improved thermostat.

Fig. 11 is a side elevation of the thermostat shown in Fig. 10 with parts of the casing broken away, and;

Fig. 12 is a fragmentary side elevation of 105 the ratchet pawls raised for actuating the carriage.

In Fig. 1 is shown a street railway car 10 upon the floor 11, on which is mounted a ventilating fan 12 driven by an electric 110 motor 13. This is positioned at one end of the car, the eye of the fan being connected

with an intake duct 14 extending along the side of the car up at the opposite end at 15, extending through the roof, the opening being provided with a grating or screen 16.

5 The delivery duct 17 leading from the fan extends from the discharge opening 18, along the inner side of the inlet duct 14 being inset therein so as to be inclosed upon three of its sides. A plurality of openings 10 19 are provided in the duct 17 for the passage of the air out into the car. The inlet duct 14 preferably surrounds three sides of the outlet for the heated air, throughout its length, or particularly the length of the 15 heater-containing area of said outlet duct, in order to partially warm the air before its introduction into the fan. The outlet duct 17 for a short distance from its connection with the outlet of the fan at 18 is enlarged 20 as at 17' and within this enlarged section are mounted a series of heating coils 19' which serve to heat the air as it is delivered from the fan into the car.

Whereas we have shown but a single ventilating fan, together with its inlet and discharge ducts, it is obvious that if such a fan has not sufficient capacity to ventilate a car, a similar set may be mounted upon the opposite side of the car adjacent to the floor with 25 its inlet opening running out of the opposite end, from that with which the other ventilating set communicates, thus compensating for changes in direction of car-travel.

The controller is indicated at 20 in dotted 30 lines in Fig. 1 as positioned in the roof of the compartment at one end of the car, the relay 21 being mounted adjacent. We have found that it is of advantage to have the 35 thermostat 22 positioned outside of the car so that it is subject to the changes of temperature outside of, rather than inside of the car.

In Fig. 4 is shown a wiring diagram in which 23 represents a trolley line receiving 40 current through a lead 24 connected to one terminal 25 of a generator 26, the other terminal 27 of which is grounded at 28. A thermostat arm indicated diagrammatically at 29, carrying at one end a spring presser 45 roller 30 makes progressive contact with a series of points 31, 32, 33, 34, 35, 36, 37, 38, and 39. The thermostat arm is pivoted on a pin 40 and from its pivotal point a conductor 41 leads through a variable resistance 42 to the trolley arm 43, the wheel 44 of which makes contact with the trolley line 23.

The contact points 31 to 39 respectively 50 are positioned in an arc described about the pivot pin 40 of the thermostat arm and since 55 the wheel 30 is spring pressed in contact with the points, it is obvious that the progressive movement upward and downward of the arm is in a series of jumps or steps, the roller always occupying, except when in motion, a position between and in contact with

two of the pins. Any slight changes in temperature, such as would effect a sensitive thermostat are insufficient to operate our improved thermostat, as its movement is resisted by the spring pressed wheel 30 until 70 the change is sufficient to force the roller over one of the pins and into its next contact position.

The moving part of our controller comprises a carriage or slide 45 mounted in a 75 frame and free to move backward or forward except as controlled by the ratchet mechanism connected with the magnets 46, and 47. The movements of this carriage are controlled by the thermostat, and the carriage movement governs the operation of the heating devices and the connections between the carriage-operating electro-responsive devices and the thermostat. In order to clarify the wiring diagram the sliding carriage is split into three parts showing in the center, diagrammatically the electro-magnetic slide-moving appliances; directly above that the section carrying contacts which govern the electric heater, and at the 85 bottom, the section carrying the switches for controlling the thermostat circuit connections.

In general, it will be understood, the opposite carriage movements are effected by 90 the two magnets 46 and 47. The circuits for these magnets are controlled by respective relays, 54, 54' and the circuits for each relay is controlled by the thermostatic switch, 29, by switch mechanism on the slide itself 100 (lowest section) and by a switch 53 or 53' moved by the armature of the respective carriage-moving magnet. This, in order that thermostat movement, completing a relay circuit otherwise closed, may cause actuation of the carriage-moving magnet, the activity of which breaks the relay circuit to permit retraction of the magnet-armature, such armature retraction moving the carriage to "kill," or open, the just-used connection from the thermostat and prepare the carriage-moving devices for appropriate response to a succeeding movement of the thermostat switch in either direction.

Directly in front of the adjacent ends of 110 the cores of the magnets 46 and 47 are slidably mounted the two armatures 48 and 48' normally held away from the magnets by the armature-connecting springs 49. Ratchet pawls 50 and 50' are pivotally connected to the armatures and engage with oppositely disposed ratchet teeth 51 and 51' carried by the slide 45. Rods 52 and 52' are connected to the armature 48 and 48' and on their opposite ends they coat with the 120 movable parts of the switch 53, 53'.

It is obvious that in the mechanism as shown in the wiring diagram, movement of the carriage could not be obtained by the 130 operation of either of the magnets, owing

to the locking effect of the pawl on the other magnet. We have provided however in our controller, which we will later describe in detail, a mechanical release mechanism interconnecting the two pawls so that when one is moved backward over a tooth into position to be advanced by the spring and move the slide, the other is automatically disengaged to permit such movement.

10 Relays 54 and 54', operating switches 55 and 55' connected in series with the respective magnets 46 and 47, are energized through the medium of the sliding contact bars 56 and 57 operating across the contact

15 fingers 58, 59, 60, 61, 62, 63 and 64.

On the side of the carriage opposite to that carrying the sliding contacts 56 and 57 are mounted two contact strips 65 and 66 together with pins 67 and 68 which pass 20 through the carriage making contact at proper intervals with fingers on opposite sides thereof. On the upper side of the frame extending over the carriage are positioned the contact fingers 69, 70, 71, 72 and 25 73 and on the lower side are mounted contact fingers 74, 75, 76.

Before describing in detail the instrumentalities whereby we obtain the various movements and control the various parts, we 30 will first describe the general operation of the system as illustrated in Fig. 4.

For convenient reference to the various positions of the carriage the letters A, B, C, D and E are placed opposite the points occupied by the right hand end of the carriage in its various positions as moved forward or backward by the operation of the ratchet pawls 50 and 50' upon the ratchet teeth 51 and 51'. Considering the carriage at the extreme right hand position indicated by letter A as shown in the diagram, the first upward movement of the thermostat arm 29 due to a decrease in temperature, will bring the roller 30 in contact with the pin 31. The pin 31 is connected by means of a wire 77 with the finger 63. In the position shown this finger 63 is out of contact with either of the slides 56 or 57 and no current will flow. As the temperature continues to decrease the thermostat arm 29 will move forward until it occupies the position between the pins 31 and 32. As the pin 32 has no outside connection no change takes place until the arm 29 moves still farther upward throwing the 55 roller into position between pins 32 and 33.

Pin 33 is connected by the lead 78 with contact finger 62 and as this is in engagement with slide 56 current will flow through the following circuit: from the line wire 23, 60 through trolley 43, resistance 42, over the wire 41, through the arm of the thermostat 29, to contact pin 33, through lead 78 to spring finger 62, into the slide 56, out through the spring finger 58, through wires 65 79 and 100 to switch 53', over the wire 80

to relay magnet 54' and ground at 81. Current flowing through this circuit energizes the relay 54', closing the switch 55'. This completes the circuit for magnet 47 through the trolley 43, wires 82, 83, 84, 85, 86, the switch 55', the wire 87, magnet 47, wire 88 to ground at 89. Energizing the magnet 47 draws the armature 48 against the core, slipping the ratchet pawl 50' back over one tooth of the ratchet 51' and forcing the rod 52' back to open the switch 53'. Opening the switch 53' deenergizes the relay 54', consequently opening the circuit through the magnet 47 permitting the spring 49 to draw the armature 48 away from the magnet and move the sliding carriage to the left one step or notch. This movement throws the carriage with contact strip 56 to the left to position B taking it away from under finger 62 and breaking the control circuit, "killing" the connection of thermostat-point 33. Current flow to accomplish these results is only momentary. The contact 33 being now dead, no further advance movement of the carriage can take place until thermostat arm 29 reaches the next live contact 35. The carriage-movement, however, moves strip 57 over to connect fingers 64-63. This 80 85 potentiates the connection 77 for the thermostat contact 31, which initially was 90 "dead" as described, and prepares the electro-responsive devices to move the carriage back to initial position should thermostat arm 29 return to contact with point 31.

Touching the electric heater control, this 100 movement of the carriage one step to the left into position B throws the contact 65 to the left carrying it under contact finger 72. This completes the circuit through trolley 43, wires 82, 83, 84, 101 to fan motor 105 13, through wire 103 to spring finger 72, through slide 65 and out through finger 73, wire 104 to ground at 105, and starts the ventilating fan in operation. The heating coils X, Y, and Z are connected at one side 110 to the wires 106, 107, and 108 to the spring fingers 71, 70 and 69, respectively. The other ends of X and Y are connected through wires 109, 110 to fingers 75 and 74 respectively, and the opposite end of coil Z 115 is connected through wire 111 to wire 112 which is connected at one end to spring finger 76 and at the other end to the wire 83 leading to the trolley.

The next upward step of the thermostat 120 throws the wheel 30 into position between the pins 33 and 34 without in any way effecting the controller. On a further decrease in temperature the thermostat arm will be thrown up another step until the wheel 30 125 is positioned between contact pin 34 and 35. Current will instantly flow through from the trolley 43, through the circuit 42, 41, 40, 29, 30, 35, wire 113, finger 61, slide 56, finger 58, wire 79 and through the relay 130

circuit previously traced to ground at 81. The magnet 47 will then be energized through the circuit previously traced and the carriage moved to point C. This carries 5 the slide 56 out from under contact finger 61 and breaks the operating circuit. When in this position the circuit for the heating coils will be as follows, the fan still remaining in circuit: from the trolley 43 through 10 wires 82, 83, 112, 111, to coil Z, wire 108, finger 69 through pin 67, spring finger 74, wire 110, coil Y, wire 107, spring finger 70; pin 68, finger 75, wire 109, coil X, wire 106, spring finger 71, contact bar 65, wire 104 15 and to ground at 105. The fan circuit through wire 103, slide 65, and wire 104 to ground 105 remains closed.

Still further upward movement of the thermostat arm 29 brings the roller 30 into 20 engagement with the contact point 37 causing current to flow through the wire 114 to finger 60 and thence through the relay circuit previously traced. This again energizes the magnet 47 causing the carriage to 25 move to the left another notch and into position indicated at D. As this movement is due to a lowering of the temperature outside the car it is essential that greater heat be radiated from the coils X, Y and Z to 30 maintain the interior of the car at a comfortable temperature. This motion of the carriage disconnects the coils from series relation and places coils Y and Z in series and the coil X directly across the line. This 35 placing of the coils, two in series and one in parallel will increase the heat radiated from the coils and raise the temperature of the car, through the medium of the heated air flowing through the delivery duct from 40 the fan.

The next step up of the rheostat arm 29 causes the roller 30 to contact with the pin 39 sending current through the wire 115 and into the relay circuit. This causes another step up of the carriage throwing it to 45 the left into a position indicated by E. The coils are then connected in parallel across the line and their maximum heating efficiency is obtained.

50 It is obvious that more coils may be used and further steps or jumps of the carriage utilized to increase the heating capacity, such provisions depending on the conditions to be met where the apparatus is installed.

55 It will be observed that each step of the slide, "killing" the point of the thermostat with which arm 29 then coacts, cuts into potential condition the formerly-dead contact of the thermostat previously passed by the 60 arm 29, and it will be observed that the slide 57 which so potentiates the passed contacts is connected with relay 54. Thus while the contact bar 56, when the carriage is in position E, is at a point where its right 65 hand end is between the two spring fingers

58 and 59, and no current can flow through the wire 115, the contact bar 57 is now in a position where it engages with contact fingers 60, 61, 62, 63, and 64. With a rise 70 in temperature the roller 30 will drop down away from the contact 39 and make contact with pin 37. Current will then flow from the trolley 43 to resistance 42, through wire 41, arm 29, roller 30, pin 37, wire 114, spring finger 60, slide 57, spring finger 64, wires 75 116 and 117 through the switch 53, wire 118, into the relay 54, out through wire 119 and to ground at 120. The relay 54 being energized causes the closure of the switch 55 permitting current to flow from trolley 80 43 through wires 82, 121, 122 through the switch 55, wire 123, through magnet 46, out to wire 124, to ground at 125. Energizing the magnet 46 draws the armature 48 against the resistance of the spring 49, slipping the pawl 50 back over one of the ratchet teeth 51 and at the same time through the medium of the rod 52 breaking contact at the switch 53 and permitting the spring to draw the carriage or slide one step to the 90 right. This brings the slide back into the position indicated at D and it is obvious that further movement of the thermostat arm 29 downward will cause subsequent steps or jumps of the slide to the right 95 through positions C, B and back to A.

At any intermediate point on the downward travel should a change in temperature cause the rheostat to reverse its movement the magnet at the opposite end of the slide 100 will be energized and the carriage thrown back one step throwing the coils into the position occupied prior to the last step.

The apparatus and circuits outlined provide for positive movement in one direction 105 or the other of a controller member, responsive to thermal changes. The movement in one direction causes first the starting of a ventilating fan, then the introduction of three heating coils in series, subsequently the 110 introduction of two coils in series and one in parallel and lastly introducing all of the coils in parallel with the line. The reverse movement of the controller first cuts out the coils connected in parallel and connects two 115 in series and one in parallel, the next step cuts them all in series, the next step cutting out the coils entirely and the last step cutting out the fan. As a result we have a system which automatically cares for itself 120 and positions the controller at the proper point in direct response to temperature changes.

Whereas we have shown diagrammatically in Fig. 4 appliances for the practice of our 125 invention we will now describe mechanisms which are well adapted for the commercial embodiment of our invention, and some of which we believe to be novel.

In Figs. 10 and 11 we have shown a par- 130

ticular form of thermostat which we prefer to use. This comprises a base 126 of some suitable insulating material, upon the lower end of which is mounted a pivot pin 40 carrying an L shaped arm 29. This arm may be of sheet metal and is provided at the end of the shorter leg with an aperture 127 in which is connected one end of a spring 128, the other end of which is connected to a pin 129 secured to the base 126. The spring is normally in tension and tends to throw the longer leg of the arm to the left.

The upper end of the arm 29 is slotted out as at 130, to receive a rod 131 of less width than the slot and upon the upper end of which is mounted a wheel 30. The lower end of the rod 131 is guided and held in its plane of movement by the strip 132 bent around and secured to arm 29 near the bottom of slot 130. Cross bars 133 extend across the open end of the arm 29 and carry the upper end of the spring 134, the lower end of which is connected to a pin extending through the lower end of rod 131. The spring is normally in tension tending to force the arm up and consequently pressing the wheel 30 against a series of pins numbered 31 to 39 inclusive, every other one of which, as already described forms a terminal contact for one of the wires 77, 78, 113, 114, and 115, the other ends of which are connected with the controller. The motion of the spring pressed roller contact from one live pin to another is quick and positive in movement due to the pressure of the spring, together with the side motion of the arm 131 within the slot 130 and sparking and wearing away of the contacts is prevented.

In order to insure the proper movement of the arm 29 in response to thermal changes we have provided a long tube 135 made of some such material as hard rubber, having a high coefficient of expansion, with its lower end abutting against a lug 136 pivoted to the shorter end of the L shaped arm 29 intermediate the pivot point 40 and the aperture 127. The upper end of the tube 135 abuts against a fixed rod 137, the upper end of which is threaded and secured in position on the lug 139 by the lock nuts 138. In order that the tube 135 may be held in proper position in alinement with the rod 137 and the lug 136, we inclose the same in a metallic tube 140, the lower end of which is pinned to the lug 136 and the upper end of which slidably engages the exterior of the rod 137. It is obvious that an elongation of the tube 135 due to an increase in temperature will cause movement of the roller or wheel 30 to the right across the contacts 39, 38, 37, 36, 35, 34 and 33. A shortening of the rod, due to contraction responsive to a lowering of the temperature permits the spring 128 to throw the arm 29 with its roller 30 backward across the contacts in reverse order.

In Figs. 5, 6, 7 and 8 is illustrated a specific controller mechanism for actuating the fan motor and heating coil circuits in response to the thermostat. The numeral 141 represents a base or support of suitable insulating material within an opening 143, in which is slidably mounted the carriage 45, the carriage being supported upon inward extending lips 144, at each side of the opening. The contact strips 65 and 66 together with the spring fingers 70 to 76 as already described in connection with the wiring diagram in Fig. 4 are mounted at one side of the frame and sliding carriage in the same relation as shown in Fig. 4. The contacts 67 and 68 are short rods of conducting material positioned vertically in openings formed in the sliding carriage which is of a suitable insulating material.

On the opposite side of the frame from that carrying the spring fingers 69 to 76, are positioned the spring fingers 58 to 64 inclusive, contacting with the slide bars 56 and 57 mounted on the carriage.

At each end of the opening 143 in the frame are mounted the actuating magnets 46 and 47 in front of which are positioned the sliding armatures 48 and 48'. These armatures are carried by the rod 52—52' which in turn are slideable within the supports 144, 95 145 and 144' and 145', which carry the magnets. At the other ends of the rods 52 and 52' are positioned the single throw switches 53 and 53' already described in connection with the wiring diagram in Fig. 4. The switch members 53 and 53' are pivoted to the support at 146 and 146' and carry at their inner ends yokes 147 and 147'. The outer ends of the rods 52 and 52' are threaded to receive elongated nuts 142 and 142' which are drawn by the springs 49 up into contact with the magnet supports 144 and 144'. Adjustment of the nuts 142 and 142' permits variations in the length of throw of pawls 50 and 50'. Depending arms 148 and 148' of insulating material are carried on the ends of the rods 52 and 52' between the nuts 142, 142' and lock nuts 142^a, 142^b. The lower ends of the arms 148 and 148' extend between the finger of the yokes 147 and 147' and into slots 148^a and 148^b in the base. The engagement of the downward extending arms in the slots provides proper guidance for the armatures holding them horizontal.

The yokes permit of a slight lost motion so that the armatures on approaching their magnets are permitted to acquire sufficient velocity to carry the ratchet 50 or 50' over the ratchet teeth before throwing the switches 53 or 53', deenergizing the magnets.

Brackets 150 and 150' are secured to the frame in front of the armatures 48 and 48' to limit their motion toward one another. These strips have upward extending ears to 130

which are secured the two parallel side bars 152, extending along each side of the ratchet tooth bars 51 and 51'. The ratchet pawls 50 and 50' are pivoted at their rear ends to lugs projecting from the armatures 48 and 48' and extend to points approximately midway of the opening 143.

The ratchet pawls 50 and 50' are of peculiar shape and are provided with an interconnecting mechanism whereby when one pawl is drawn back over a ratchet tooth, the opposite pawl is raised from engagement with its rack so as to permit the other ratchet on its forward motion under the influence of the springs to move the carriage. The active ends of the ratchet pawls 50 and 50' are shaped with downward extending thumbs 153 and 153' which engage with the ratchet teeth 51 and 51' respectively. Extending upward at an angle to the thumbs 153 and 153' are fingers 154 and 154' terminating at their ends in downward extending hook parts 155 and 155'. Pins 156 and 156' extend outward from each of the pawls near the juncture of the thumbs and fingers and carry on their ends the links 157 and 157' through engagement with the slots 158 and 158'. The forward ends of the links 157 and 157' carry inward projecting dogs 159 and 159' which extend into the openings formed by the thumbs 153, 153' and hooks 155 and 155'. The dogs 159 and 159' also carry short levers 160 and 160' which extend backward at acute angles to the links 157 and 157' terminating in pins 161 and 161' pivoted in the side rails 152.

The operation of the ratchet pawls is as follows. Supposing for example that the magnet 46 is energized drawing backward 40 the armature 48, the first rearward movement of the pawl 50 will carry the thumb 159 upward on the inclined tooth of the ratchet 51 until the pin 156 reaches the end of the slot 158. This point will be just 45 prior to the dropping of the thumb 153 over the top of one of the ratchet teeth. On engagement of the pin 156 with the end of the slot 158 the link 157 is drawn backward pivoting on the pin 161 and raising the dog 50 159. The upward movement of the dog 159 causes its engagement with the finger 154' with the result that the ratchet pawl 50' with its operating thumb 153' is raised out of engagement with its ratchet teeth. This 55 lifting of the pawl 154' continues until link 157 throws dog 159 past the nub 154', the engagement of which holds pawl 154 raised. By this time the thumb 153 has dropped down into the next ratchet tooth and the 60 armature 48 is ready for retraction. When springs 49 retract the armature to move the carriage pin 156 travels the length of its slot, releases the latch dog 159 and allows pawl 50' to drop back into the next tooth 65 pocket of its rack. At the end of this move-

ment the ratchets are both in engagement with their teeth and the carriage is positively locked against further movement until one of the magnets 46 or 47 is again energized.

The springs 49 are secured to the movable parts of the armatures 48 and 48' by engagement with the ends of the rods 162 and 162' which pass through openings in the ends of the pawls 50 and 50' adjacent 75 their point of pivotal connection with the armature.

In Figs. 2 and 3 we have illustrated our improved form of heater which is easily made up without special castings or stamping. A plurality of spiral strips 163 of sheet iron or similar material are secured at one end to a rod 164 and carry at intervals insulating rods 165 secured to the strips by U bolts 166. On this open frame are wound 80 heating coils 167 formed from wire having a relatively low coefficient of conductivity. One terminal of each heating coil 167 is secured to a suitably formed insulator and extends outward adjacent the rod 164. The convolutions of the first coil, as illustrated in Fig. 3, extend outward around the curves of the frame in a plane at right angles to the axis of the rod 164 to a point 168 at its outer end. At this point the coil is bent 85 over parallel with rod 164 to a point somewhat removed from the first section and there extends inward in a series of coils down to the rod 164. It is then carried along the rod 164 around a suitable insulating 90 sheath 169 and again run outward around the conformation of the frame to form a second unit.

This method of forming the heating coils is so flexible and simple that the required 105 length of wire for properly heating the air passing through the duct 17 is readily placed within the enlargement of the duct 17'. In the embodiment of the invention shown three sets of coils X, Y and Z are used. 110 Each set of coils may comprise any number of spirals, and it is obvious that more or less coils may be used depending on the required heating capacity of the system.

In the system and apparatus above described it is evident that various changes may be made in order to adapt it to particular environments. In some instances it may be found necessary to use a large number of heating units and consequently use 120 a controller having more than five steps or jumps to operate the units. Again in some instances it may be found desirable to locate the thermostat within the area to be heated and ventilated, though we have found that 125 in street car work or in fact in any work where the compartment to be heated is poorly insulated from the surrounding atmosphere, it is most desirable to have the thermostat exposed to the outside tempera- 130

ture in order to properly condition or prepare the interior for changes due to outside temperature changes. Whereas in the system shown the ventilating fan is connected 5 through the controller, in some instances it may be advisable to bridge over a circuit for the fan so as to permit its operation independent of the thermostat.

Whereas we have illustrated and described 10 a particular embodiment of our invention, it is obvious that various changes in the wiring and in the arrangement of controller contacts may be made without departing from its spirit and scope.

15 Having described our invention, what we claim is:—

1. In an automatic heat controlling system, the combination of an arm movable to various positions in response to thermal 20 changes, a plurality of contact points in the path of said arm, a controller having a movable part, means responsive to the engagement of said arm with the contact points for moving said controller part from one 25 position to another, a source of current supply, electrical heating coils and switches operated by the movement of said controller for connecting said coils in various relations to the line.

30 2. In an automatic heat controlling system, the combination of an arm movable to various positions in response to thermal changes, a plurality of contact points in the path of said arm adapted to be progressively 35 engaged thereby, a controller having a part movable step by step in either direction; means responsive to the engagement of said arm with the contact points for moving said controller part step by step from one position 40 to another, a source of current supply, a plurality of electrical heating coils, and switches operated by the movement of said controller part for connecting said coils in various relations to the source of current 45 supply.

3. In an automatic heat controlling system, the combination of an arm movable to varying positions in response to thermal changes, a plurality of contact points in the path of said arm, and adapted to be progressively engaged thereby, a controller having an electro-magnetically controlled part movable step by step in either direction, circuits including said arm and contacts for operating the electro-magnetically controlled part, a source of current supply, electrical heating coils, a plurality of switches operated by the movement of said controller part for connecting the coils in various relations to the source of current supply.

4. In an automatic heat controlling system, the combination of a thermostat, a controller having a movable part, means con-

nected with the thermostat for moving said controller part in response to thermal changes, a ventilating fan motor, a series of heating coils in the discharge duct of said fan and switches operated by the movements of said controller part for connecting 65 the said fan motor and heating coils in circuit with a source of current supply.

5. In an automatic heat controlling system, the combination of a thermostat, a controller having a movable part, means connected with the thermostat for moving said controller part in response to thermal changes, a ventilating fan motor, heating coils in the discharge duct of said fan and switches operated by the movements of said controller parts for connecting said fan motor and heating coils in circuit with a source of current supply, said switches being arranged to include the fan motor in circuit with the source of current supply whenever 80 the heating coils are in circuit.

6. In an automatic heat controlling system, the combination of a thermostat, a controller having a slidable carriage, electric motors operatively connected with the said carriage for moving it from one position to another, a plurality of contact points adapted to be engaged by said thermostat in its progressive movement, electrical connections between the said plurality of thermostat 90 points and the carriage actuating motors, heating coils, a source of current supply, and switches operated by said sliding carriage for connecting the heating coils in various relations with a source of current 95 supply.

7. In an automatic heat controlling system, the combination of a thermostat, a controller having a sliding carriage, electro-responsive means for moving said carriage 105 from one position to another, means for momentarily energizing said electro-responsive means in response to movement of the said thermostat, a plurality of heating coils, contact fingers positioned adjacent the carriage and connected to the said coils, contact fingers similarly placed and connected with a source of current supply, and contact strips movable with said carriage and adapted to engage with the said fingers and 110 cut the said coils in or out of the source of current supply.

8. In an automatic heat controlling system, the combination of a thermostat, a controller having a movable part, electro-responsive means for moving said movable part of the controller in response to movements of the thermostat, a fan operating motor, a plurality of heating coils, positioned in the discharge of the fan, a source 120 of current supply, switches operated by the said controller moving part, whereby movement of the controller part in one direction 125

first connects the fan motor with the source of supply, then the coils in series and lastly the coils in parallel.

9. In an automatic heat control system, 5 the combination of a controller having a sliding carriage, electro-responsive means for moving the said carriage in a step by step motion, a thermostat having progressive engagement with a plurality of contact pins, 10 electrical connections between the said pins and a series of contact fingers adjacent the sliding carriage; a source of current supply, contacts on the said carriage adapted to engage all but one of the said fingers and 15 connections between the said contacts and the electro-responsive means.

10. In an automatic heat control system, 20 the combination of a controller, having a movable member, electro-responsive means for moving said member step by step, a thermostat having progressive engagement with a plurality of contacts, a series of fingers adapted to engage said movable member, electrical connection between said contacts and fingers, a source of current supply, 25 contacts on the movable member arranged to engage all but one of the said fingers, and connections between the last mentioned contact and the electro-responsive means.

11. In an electrical heating coil the combination of a central supporting rod, a plurality of strips extending outward in spiral formation from the rod, and spaced from each other, insulating rods parallel to the 35 supporting rod and carried by said strips, and electrical heating wires carried by the said insulating rods.

12. In an automatic heat controlling system, a movable member, heating means controlled by said member for increase or decrease of heating effect as said member moves in one direction or the other, electro-responsive means for imparting step by step movement to said member in either direction, and a thermostat controlling said electro-responsive means.

13. In an automatic heat controlling system, a movable member, heating means controlled thereby for increase or decrease of

the heating effect as said member moves in 50 one direction or the other, electro-responsive means for imparting step by step movement to said member in either direction, switches controlled by movement of said member, a thermostat having a movable contact and a 55 plurality of temperature indicating contacts, and circuit connections for said electro-responsive means governed by the thermostat contact and controlled by said switches for connecting all temperature contacts on one side of the movable contact to operate said step by step means in one direction and on the other side of the movable contact to operate said step by step means in the opposite direction.

14. In an automatic heat controlling system for street cars or the like, the combination of a thermostat positioned outside of the car, a controller having a movable part, 70 means connected with the thermostat for moving said controller in response to outside thermal changes, a ventilating fan having inlet and discharge ducts, a motor for driving said fan, a series of heating coils in the discharge duct of said fan, the inlet duct 75 opening outside the car, and switches operated by the movements of said controller part for connecting the said fan motor and heating coils in circuit with a source of current supply.

15. In an automatic heat controlling system for street cars or the like, the combination of a movable member, heating means within the car controlled by said member for increase or decrease of heating effect as said 85 member moves in one direction or the other, electro-responsive means for imparting step by step movement to said member in either direction, and a thermostat positioned outside of the car and controlling said electro- 90 responsive means.

In testimony whereof we hereunto set our hands.

JOHN K. NORSTROM.
GEORGE C. BREIDERT.
